DESIGN FOR A FOUNTAIN PEN BARREL OR SIMILAR ARTICLE

Garfield L. Beckstrom, Chicago, Ill., assignor to Autopoint Company, Chicago, Ill., a corporation of Illinois

Application January 23, 1946, Serial No. 125,847

Term of patent 14 years

(Cl. D74—17)

To all whom it may concern:

Be it known that I, Garfield L. Beckstrom, a citizen of the United States, residing at Chicago, in the county of Cook and State of Illinois, have invented a new, original, and ornamental Design for a Fountain Pen Barrel or Similar Article, of which the following is a specification, reference being had to the accompanying drawing, forming a part thereof.

In the drawing:

Figs. 1, 2 and 3 are elevational views of the fountain pen barrel, showing my new design when rotated in different positions.

I claim:

The ornamental design for a fountain pen barrel or similar article, substantially as shown.

GARFIELD L. BECKSTROM.
